ATTORNEY.

UNITED STATES PATENT OFFICE.

HENRY WALDEN, OF PHILADELPHIA, PENNSYLVANIA.

BUTTONHOLE.

SPECIFICATION forming part of Letters Patent No. 788,078, dated April 25, 1905.

Application filed August 9, 1904. Serial No. 220,081.

To all whom it may concern:

Be it known that I, HENRY WALDEN, a citizen of the United States, residing at Philadelphia, in the county of Philadelphia and State of Pennsylvania, have invented certain Improvements in Buttonholes, of which the following is a specification.

This invention relates more particularly to buttonholes for shoes; and it has for its object to provide staying means protected by a blind which effects a neat appearance and prevents the chafing of the buttons and stitching.

In the accompanying drawings, Figure 1 represents a side elevation of a shoe having the improvements applied thereto, and Fig. 2 represents a section of the improved shoe-lap having the lining turned back.

As shown in the drawings, the shoe-lap 1 has the outer fabric or leather 2 provided with the buttonholes 3, preferably consisting of a slit 3', terminating in a small eye 3'', forming a comparatively small hole in registration with the larger holes 4 in the inner or lining fabrics 5 and 6. The lining fabrics are connected together by the stitching 7, preferably extending around the holes, and by the stays 8 set in the eyes of the holes in position to take the wear from the buttons 9, the stays being preferably of metal. The outer fabric 3 is connected to the lining fabrics 5 and 6 in the usual manner, excepting that the outer fabric is preferably not sewed to the lining around the buttonholes, though this may be done.

When the shoe is buttoned, the lips 10 of the holes 3 fit snugly around the buttons 9, forming a blind covering the stitching and stays of the inner and larger holes 4, which take the strain, the lips also acting as a protection to prevent chafing between the buttons and the stitching and the stays.

As the outer fabric or member is flexible and free about the holes cut therein, as the construction permits the holes in the lining members to be made comparatively large, and as the freedom of the outer fabric reduces the

rigidity due to sewing the outer fabric and lining together around the buttonhole, the flexibility of the material around the holes is greatly increased and the shoe can readily be 50 buttoned with the fingers without the use of a hook.

Having described my invention, I claim—

1. In a shoe, a lining having a buttonhole therein and an outer leather having a buttonhole therein registering with and covering the edges of said first buttonhole, said outer leather and said lining being detached about said buttonholes, substantially as specified. 55

2. In a shoe, a lining having a buttonhole 60 therein, a stay for supporting said buttonhole, and an outer leather having a buttonhole therein registering with said first buttonhole, said outer leather covering said stay, and the edges of said first buttonhole substantially as speci- 65 fied.

3. In a shoe, lining members having a buttonhole therein, a stay and stitching for supporting said buttonhole, and an outer leather having a buttonhole therein registering with 70 said first buttonhole, said outer leather being detached from said lining members around said buttonholes and covering said stay and stitching, substantially as specified.

4. In a shoe, an upper comprising lining 75 members having registering holes therein, means for securing said members together around said holes, and an outer leather member having holes therein registering with the holes in said lining members, said outer member extending beyond the edges of the holes of said lining members and covering said means for connecting them, substantially as specified. 80

In testimony whereof I have hereunto set 85 my hand, this 5th day of August, 1904, in the presence of the subscribing witnesses.

HENRY WALDEN.
